MASK

George Hanft, deceased, late of Irvington, N. J., by Susan
M. Hanft, administratrix, Irvington, N. J.

Application December 30, 1955, Serial No. 39,525

Term of patent 14 years

(Cl. D34—15)

Figure 4 is an elevation of one end thereof, the other end being the same;

What is claimed is:

The ornamental design for a mask, as shown.
